CARRIER FOR CHILDREN'S SHOES

Frank R. Fogertey, Jr., Kirkwood, Mo.

Application August 12, 1957, Serial No. 47,342

Term of patent 14 years

(Cl. D58—12)

Fig. 1 is a side elevational view of a carrier for children's shoes, showing my new design;

Fig. 2 is a top plan view thereof;

Fig. 3 is an end elevational view thereof taken from the left side of Fig. 1; and

Fig. 4 is a perspective view thereof showing the side opposite to that of Fig. 1.

I claim:

The ornamental design for a carrier for children's shoes, as shown.
